UNITED STATES PATENT OFFICE

2,105,815

SHIP FENDER

Elov F. Maas, Cuyahoga Falls, Ohio, assignor to
Wingfoot Corporation, Wilmington, Del., a cor-
poration of Delaware

Original application January 8, 1934, Serial No.
705,749. Divided and this application October
17, 1936, Serial No. 106,205

9 Claims. (CL. 114—219)

The present invention relates to an improvement in marine fenders and it has particular reference to such fenders which are used for protecting the sides of a ship from injury in the event of contact or collision with other marine structures, such as piers, break-waters, canal locks and the like. They may be used on piers, break-waters, etc., or on the ship itself.

This application is a division of my application 10 705,749 filed Jan. 8, 1934, for Marine fender.

Prior to this invention, several types of marine fenders have been proposed, but they have been objectionable for several reasons. Most of them have been too rigid and unyielding to give 15 the necessary cushioning effects, and some have been too costly because of complicated structure and difficulty in applying. The present invention, however, overcomes the objectionable features of the prior art and provides a fender of extreme simplicity in construction and one which 20 may be easily installed or applied.

An important object of the invention is to provide a marine fender which will be formed of cushioning material, preferably resilient rubber, 25 and so arranged as to be flexible throughout at least the major portion of its length.

Another object is to provide a marine fender which will be not only formed of yieldable material, but which will be yieldably supported so as 30 to be capable of complete bodily movement when necessary.

Another object is to provide such a fender which will be capable of movement both horizontally and vertically, and this without likelihood of the cushioning material being torn away 35 from its supporting means.

An important object of this invention is to provide supporting means on a fender which is securely locked in place with respect thereto, the 40 supporting means being adapted to be secured either to the ship or to the pier, break-water or the like by a suitable fastening means.

The foregoing and other objects, features and advantages of the invention will be readily appreciated from the following description in conjunction with the accompanying drawing, wherein several forms of the invention have been shown by way of illustration, and wherein:

Fig. 1 is an elevational view of a marine fender 50 embodying my invention;

Fig. 2 is an enlarged longitudinal cross-sectional view of one end of the marine fender shown in Fig. 1;

Fig. 3 shows a modified means for supporting 55 the marine fender;

Fig. 4 is an end elevation of the device shown in Fig. 3;

Fig. 5 is an enlarged longitudinal cross sectional view through the device shown in Figs. 3 and 4 taken substantially along the line 5—5 of Fig. 4 showing the means for attaching the supporting means to the fender proper; and

Fig. 6 shows somewhat the action which takes place when the marine fender is compressed between a ship and a pier or the like when the ship 10 is docking or is thrown toward the pier by the waves.

It will be noted from an inspection, particularly of Figs. 1, 2, 3, and 7, that the tubular body 15 of flexible material, such as rubber, has a relatively large inner diameter so that the same may be compressed appreciably and give a resilient action which prevents the fender from being pounded to pieces, as would an ordinary solid member.

In Figs. 1 and 2 this tubular member, of which there may be one or more provided on any given structure, is shown as being provided with tapered plugs 29, which may also be formed of rubber and provided with longitudinal bores 30 25 for the passage of the flexible supporting cable 16. A substantially cylindrical metal bushing 31 is anchored in the outer end of each of the tapered plugs 29, said bushing being centrally bored in alignment with the bore 30 to accommodate 30 the cable 16. In this construction the cushioning properties of the rubber are augmented by the air which is confined within the tubular member 15 so that this particular form of fender is in fact of the pneumatic type. Yet it is 35 suspended in such a way as to be bodily movable along the cable and to be rotatable thereabout, so that when a ship is at a pier with the fender between the ship and the pier or the like the fender may rotate about a substantially horizontal axis as the ship rises and falls with the swells, and may also slide longitudinally along the cable in the event that the ship moves in that direction or during the time when the ship is docking.

In some installations it might not be desirable 45 to employ the longitudinally extending supporting member within the rubber cushioning tube, and in that event a structure as shown in Figs. 3 to 7 inclusive may be employed. Here the cushioning tube 15^a is provided in one of its side walls 50 with a plurality of relatively spaced anchoring plugs 33 having their outer surfaces corrugated or otherwise roughened and molded in place, whereby to be well bonded. Each of these anchoring plugs 33 is formed with a dove-tail socket 55

34 into which the lower end of a suspension cable 20 may be inserted. The lower end of the suspension cable is flared or enlarged (see Fig. 6), as at 35, and the space between the flared end 5 of the cable and the socket is thereafter filled with molten lead 36 or the like for the purpose of holding the parts in assembled relation.

In Fig. 7 the fender 15 is shown arranged between a ship 37 and a pier 38 with the suspension cables 20 therefor connected to the pier at their ends by means of a staple 40 embedded in concrete. Obviously, any other form of fastening means may be used for this purpose. As the ship moves toward the pier, as in Fig. 7, the tubular member 15 is compressed and substantially entirely flattened out so that there is no opening 10 interiorly thereof, although ordinarily the rubber in the fender is sufficiently thick so that the fender is not completely flattened out but retains 15 some of its original shape. In the event that a structure such as shown in Figs. 1 and 2 is employed, the compression of the rubber fender is not as complete as that illustrated in Fig. 7, due 20 to the solid portions provided at the end of the fender. The advantage of the constructions shown in Figs. 1 and 2, however, is that, since 25 there is very little air that can escape through the bore 30 if the fender is sufficiently compressed, the air within the fender is confined and acts as 30 an additional cushioning means for resisting the flattening of the fender itself.

From the foregoing it will be understood that a novel marine fender has been provided which will be capable of absorbing shocks incident to 35 the contacting of a pier by a ship and thus protecting the sides of the ship from injury. The construction is extremely simple and capable of being produced at relatively low cost as well as being capable of easy installation. The fenders 40 need not necessarily be employed upon a fixed marine structure, but may be used to equal advantage when suspended at the side of a ship, and in this respect the term "marine structure" has been employed in the specification and claims in 45 its broad significance to include either a fixed structure such as a pier or the like, or a movable structure such as a ship or equivalent. Furthermore, the fenders are not limited to use in a 50 horizontal position, but may be suspended vertically or otherwise as desired. Obviously the invention may be modified in respect to details other than those specifically illustrated and described, and the right is herein reserved to make 55 such changes as fall within the scope of the appended claims without departing from the spirit of the invention.

Having thus fully described my invention, what I claim and desire to secure by Letters Patent of the United States is:

60 1. A marine fender comprising an elongated tubular member of resilient material having an internal air space therein of substantial proportions, and a plurality of suspension means anchored at intervals in one side wall of said tubular member but not extending through said space to the opposite wall for securing the same to a pier or the like.

65 2. A marine fender comprising an elongated tubular member of resilient material having an internal air space therein of substantial propor-

tions, a plurality of anchor plugs embedded at intervals in one side wall of said tubular member but not extending through said space to the opposite wall, and means secured to each of said anchor plugs for suspending said tubular member 5 from a pier or the like.

70 3. A marine fender comprising an elongated tubular member of resilient material having an internal air space therein of substantial proportions, a plurality of metallic plugs molded at intervals into one side wall of said tubular member but not extending through said space to the opposite wall, and means secured to each of said anchor plugs for suspending said tubular member 10 from a pier or the like. 15

4. A marine fender comprising an elongated tubular member of resilient material having an internal air space therein of substantial proportions, a plurality of metallic anchor plugs vulcanized at intervals in one side wall of said tubular member 20 but not extending through said space to the opposite wall, and means secured to each of said anchor plugs for suspending said tubular member from a pier or the like.

25 5. A marine fender comprising an elongated tubular member of rubber having an internal air space therein of substantial proportions, a plurality of metallic anchor plugs having ribbed rubber contacting surfaces molded at intervals in one side wall of said tubular member but not extending 30 through said space to the opposite wall, and means secured to each of said anchor plugs for suspending said tubular member from a pier or the like.

35 6. A marine fender comprising an elongated tubular member of resilient material having an internal air space therein of substantial proportions, a plurality of metallic anchor plugs molded at intervals in one side wall of said tubular member but not extending through said space to the 40 opposite wall, said anchor plugs each having a socket therein, and means secured in said sockets for suspending the same from a pier or the like.

45 7. A marine fender comprising an elongated tubular member of resilient material having an internal air space therein, and a plurality of metallic anchor plugs molded at intervals in one side wall of said tubular member, said anchor plugs each having a socket therein provided with undercut walls, and means interlocked with said 50 sockets for securing the same to a pier or the like.

55 8. A marine fender comprising an elongated tubular member of resilient material having an internal air space therein, and a plurality of metallic anchor plugs molded at intervals in one side wall of said tubular member, said anchor plugs each having a dovetail socket provided 60 therein, and a plurality of cables each having a frayed end fixed in one of said sockets by a solidified low melting point metal, for securing the same to a pier or the like.

65 9. A marine fender comprising an elongated tubular member of resilient material having internal air space therein, of a plurality of anchoring means molded in one side wall of said tubular element and suspension means associated with 70 said plurality of means for suspending the tubular element from a pier or the like.
